UNITED STATES PATENT OFFICE.

CHARLES J. WOOLSON, OF CLEVELAND, OHIO.

IMPROVEMENT IN COOKING-STOVES.

Specification forming part of Letters Patent No. 35,483, dated June 3, 1862.

To all whom it may concern:

Be it known that I, CHARLES J. WOOLSON, of Cleveland, Ohio, have invented a new and improved mode of regulating the size and operation of the fire-chamber of cooking-stoves by the introduction into the same of a framework of cast-iron, which also protects and preserves the fire-plate; and I declare that the following is a full and exact description thereof, reference being had to the accompanying drawings, and the letters of reference marked thereon.

To enable others to make and use my invention, I proceed to describe its operation and construction.

I construct a frame-work of cast-iron consisting of perpendicular flat bars, one edge of which lies against the fire-plate, while the other projects into the fire-chamber. The position and projection of the perpendicular bars are seen at A A in the drawings. These perpen-

dicular bars are attached at their upper ends to a horizontal flat bar running at right angles, which projects over the fire-chamber at an upward angle, as seen at B in the drawings. The object and use of the perpendicular bars are to protect the fire-plate, to contract or enlarge the fire-chamber, and to support the horizontal flat bar, which is intended to regulate the escape of the heat, flame, and smoke from the chamber.

What I claim as my invention, and desire to secure by Letters Patent, is—

The construction and arrangement of the perpendicular and horizontal connecting-bars in the fire-chamber of cooking-stoves, in the manner described, and for the purposes set forth.

CHARLES J. WOOLSON.
